UNITED STATES PATENT OFFICE

CORNELIUS P. HOUTSMA, OF OCHHEYEDAN, IOWA

GRAIN BINDER CONSTRUCTION

Application filed April 23, 1929. Serial No. 357,415.

The object of my invention is to provide a grain binder construction of simple, durable and comparatively inexpensive manufacture.

5 Another object is to provide a grain binder construction embodying improvements over my co-pending application filed January 7, 1926, Serial No. 79,777, and allowed November 24, 1928, which issued into Patent No. 10 1,714,025 under date of May 21, 1929.

A further object of my invention is to provide in a binder construction, a main drive shaft and a secondary drive shaft with all the operating parts of the binder driven 15 from these two shafts, whereby a direct transmission of power is obtained and consequently the elimination of loss of energy encountered where numerous operating connections are interposed between the drive shafts 20 and the final point of application of the power for running the binder.

More particularly, it is my object to provide a main drive shaft driven from the bull 25 wheel of the binder with direct connections from this main drive shaft to the packer shaft and sickle of the binder.

A further object is to provide a secondary drive shaft driven from the main drive shaft with means for driving the platform conveyor, the elevating conveyor, the floating conveyor, the transfer roller interposed between the upper end of the elevating conveyor and the binder deck and for driving the butter board.

30 Still a further object is to provide in connection with the frame of a binder in which the bull wheel is mounted, a platform having its forward end pivoted to the frame and its rear end supported by a caster wheel.

Still a further object is to support the binder seat on the platform whereby the weight of the driver is imposed on the bull wheel for better traction, the driver being positioned directly back of the team pulling the binder, whereby side draft is reduced considerably and the driver may drive in a standing position if he so desires.

Still a further object is to provide a modified form of construction in which the seat

platform is entirely suspended from the frame of the binder.

With these and other objects in view my invention consists in the construction, arrangement and combination of the various parts of my device, whereby the objects contemplated are attained, as hereinafter more fully set forth, pointed out in my claims, and illustrated in the accompanying drawings, in which:

Figure 1 is a front end elevation of a binder illustrating my improvements thereon.

Figure 2 is a plan view of the same showing some parts removed and other parts broken away and omitted to conserve space.

Figure 3 is a side elevation of the binder looking at it from the left hand side of Figure 1.

Figure 4 is an enlarged detail sectional view on the line 4—4 of Figure 3.

Figure 5 is an enlarged sectional view of a portion of Figure 3 illustrating a caster wheel shaft lock.

Figure 6 is an enlarged sectional view on the line 6—6 of Figure 3.

Figure 7 is an enlarged sectional view on the line 7—7 of Figure 3, illustrating the connection of my mechanism with the butter board; and

Figure 8 is a modified form of construction illustrating a portion of Figure 3 to show a suspension means whereby the seat platform is entirely supported on the binder frame.

On the accompanying drawings I have used the reference numeral 10 to indicate a bull wheel. In connection with the bull wheel 10 I provide a frame of improved construction consisting of a front arched frame member 12 and a similar member 14 at the rear of the frame. The frame members 12 and 14 are connected by bars 16 and 18, to which the axle brackets 20 of the bull wheel 10 are secured. The brackets 20 are part of a binder of the ordinary construction but curved differently and may be secured to the frame bars 16 and 18 by means of bolts.

The frame members 12 and 14 have extensions 13 and 15 extending to and connected with the platform 17 of the binder. A brace 19 is provided in connection with the mem-

ber 12 and the member 13 and extends forwardly to serve as a connecting arm for the tongue truck. The forward end of the brace 19 has an opening 21 for such connection.

Operatively connected with the bull wheel 10 by means of a chain 22 and clutch mechanism 24 is a main drive shaft 26 supported in bearings 28 and 30. The clutch mechanism 24 is operatively controlled by a control rod 32.

The bearing member 30 is formed on a bracket 34, which is provided with a vertical bearing 36 in which is journaled a sickle drive shaft. By means of a bevel gear connection 38, the sickle drive shaft rotates a small flywheel with crank pin 40, thereby reciprocating a connecting link 42.

The connecting link 42 is connected with the sickle bar 44.

The deck of the binder is indicated at 46 and is supported by brackets 48 extending to a sliding angle 50 and by a pulley 52. The pulley 52 is supported on bracing 55, the lower end of which is secured to a projection 53 on the bracket 34. A track member 57 on the binder frame coacts with the pulley 52. The angle 50 slides in brackets 54. A packer shaft 56 is rotatably supported in a bearing 60 secured to one of the frame bars 18, and additionally supported in any desired manner.

A sleeve 62 is journaled in the bearing 60 and is provided with a square opening for the packer shaft 56. A flange 64 is provided at one end of the sleeve 62 and a packer shaft wheel 66 is adapted to be secured to the other end of the bushing or the sleeve 62.

The packer shaft wheel 66 is provided with a plurality of radially extending rollers 68 adapted to be actuated by oval shaped blades 70 formed on a wheel 72. The wheel 72 is secured to the main drive shaft 26.

A secondary drive shaft 74 is provided and journaled in bearings 76 and 78. The secondary drive shaft 74 is operatively connected with the main drive shaft 26 by means of a bevel gear connection 80. Sprockets 82 and 84 are secured to the second drive shaft 74, as clearly shown in Figure 2. The sprocket 82 is adapted to be connected by a chain 86 with the sprocket 88 for driving the platform conveyor 90.

The sprocket 84 is adapted to be connected by a chain 92 with an elevating conveyor sprocket 94 and a floating conveyor sprocket 96. The chain 92 extends over an idler 98, which is journaled on a bracket 100. The bracket 100 is adjustable up and down in guides 102, whereby the chain 92 may be changeably tightened, as desired.

The elevating conveyor and floating conveyor rollers, driven by the sprockets 94 and 96 are indicated at 104 and 106 respectively.

Secured to the bracket 108 which has the bearings 28 and 78 formed thereon, is a bear-

ing 110 in which the lower end of an upwardly extending shaft 112 is journaled. The shaft 112 is operatively connected with the secondary drive shaft 74 by a bevel gear connection 114. The upper end of the shaft 112 is squared and fits in a square socket of a butter board shaft 116. Referring to Figures 3, 4 and 7, the butter board shaft 116 has a bevel gear 118 on its upper end provided with a crank pin 120. The crank pin 120 coacts with an actuating arm 122 on the butter board 124 in the usual manner. A pair of ears 126 extend from the butter board shaft bearing 117 and have an arm 128 pivoted thereto and connected by a link 130 with the butter board in the usual manner.

The squared shaft 112 and the square socket of the butter board shaft 116 allow for slight differences in positions of the shaft 116 relative to the shaft 112 to accommodate different slanting positions of butter boards. The butter boards on different machines are slightly different in slant and the shaft 116 may thus be adjusted square with the butter board.

The sprockets 94, 96 and the idler sprocket 98 are mounted on a plate 132 secured to the top of the frame member 12 which extends upwardly, as clearly shown in Figure 3. A cross member 134 braces the plate 132 and has a downwardly extending portion indicated at 136 in which is journaled a shaft 138. A bevel gear 140 is secured to the shaft 138 for coacting with the bevel gear 118. Also secured to the shaft 138 is a gear 142 adapted to mesh with a pinion 144 on a transfer roller shaft 146. The transfer roller is indicated at 148.

The rear lower end of the cross brace 134 is provided with a bearing 149 in which the rear ends of the roller 148 and the upper roller of the conveyor 104 are journaled.

A bearing bracket 150 may be secured to the cross member 134 for supporting the upper end of the floating conveyor 106. The cross member 134 is looped backwardly, as indicated at 152 to allow tall grain to pass therethrough. The portion 152 is provided with a cross arm 154 connected by means of braces 156 with the frame members 14 and 18. The bearing 150 is of floating type.

In connection with the binder frame I provide a platform frame consisting of side members 158 having downturned ends 160 adapted to be pivotally connected by bolts 162 to the binder frame. A platform 164 is supported on the members 158 by means of inverted U-shaped bars 166. The bars 166 are provided with a plurality of openings so that the platform 164 may be vertically adjusted relative to the members 158 and the portions 160 of the members 158 are also provided with a plurality of openings so that they may be vertically adjusted relative to the binder frame. The seat 168 usually provided in

connection with the binder is secured to the platform 164.

At the rear end of the frame members 158 I provide a vertical bearing member 170 having a vertical shaft 172 journaled therein. A supporting arm 174 extends from the lower end of the shaft 172 and a brace 176 extends from the upper end thereof.

In connection with a binder, a wheel 178 is always provided which is journaled on a shaft 180 having an upwardly extending portion 182 and a horizontally extending portion 184 of square cross section. The portion 184 terminates in a reduced round portion 186 having an enlarged head 188. The supporting arm 174 is provided with a square opening for the portion 184 of the shaft 180 and the brace 176 has an opening 190 large enough for the head 188 to extend through, after which the reduced portion 186 registers with the opening 190.

Referring to Figure 5, a spring actuated latch 192 is illustrated for the purpose of preventing removal of the shaft 180 from the members 174 and 176. A knob 194 is provided for the latch 192 to enable the same to be manipulated as desired.

The wheel 178 and shaft 180 with its portions 182, 184, 186 and 188 are originally intended for insertion in an end of the binder frame and a similar device is used for the other end for transferring the binder from one field to another. I merely design the rear end of my platform so that one of these wheels may be utilized for supporting the same. The members 174 and 176 are suitably braced and spaced by means of a brace rod 196.

Referring to the modified form shown in Figure 8, the caster wheel 178 may be dispensed with and a pair of rods 198 provided for entirely supporting the platform 164 relative to the binder frame. The ends of the rods 198 would be hooked for convenience in attaching them.

Various advantages arise from constructing a binder as herein disclosed. The mechanism of the binder is driven by direct connections so as to conserve power. The secondary drive shaft 74 is squared at its forward and rearward ends so that when a tractor is utilized for pulling the binder it may be connected with the forward end of this shaft.

The floating conveyor 106 has its upper end mounted in a slot 200 so that the upper end can float up and down depending on the amount of grain passing between the conveyors 104 and 106. The bracket 150 would be pivoted for the same purpose. It will be noted that the drive chain 92 is arranged in such a manner that the sprocket 96 may travel up and down the portion of the chain between the sprockets 94 and 98 and still be driven in any of its positions.

The driver's seat 168 is usually supported

above platform and elevating conveyors and the driver must therefore always remain seated, since even if he should have a platform to stand on when he gets tired sitting down, there would be too much danger of falling into operating parts of the binder.

I have therefore mounted the platform 164 in the rear of the binder so as to get the driver away from a position above operating parts of the binder so that he can stand on the platform when he becomes tired of sitting down without danger of falling into moving parts if he should fall from the platform.

This new position for the driver is much better from otherstandpoints. It lessens side draft, which is always considerable in a binder and which is enhanced by placing the driver in the usual position above the platform and conveyors. The new position of the driver is also much better, as he can drive his horses much better, since the new position of the seat is directly behind them. The caster wheel 178 also acts as a stabilizing rudder for the binder and assists in reducing side draft.

Referring to Figure 2 it will be noted that the supporting arm 174 is curved so that the wheel 178 is directly behind the pivot shaft 172 whereby the wheel acts in the capacity of a caster wheel.

The cross bar 134 takes the place of a light bar usually provided in binders to which the hood 47 of the binder is secured. The cross bar 134 extending rearwardly and looping back and downwardly and then secured to the rear frame member 14 makes it much more substantial and a stronger means of support for the rear floating end of the upper conveyor.

The material of the bar 134, however, may not be quite heavy enough to support the bearings in front of the plate 132 and a casting could therefore be provided for bridging the space between the downwardly extending end 136 of the cross bar 134 and the plate 132. This is merely a matter of design, however, and either such construction or the construction I show would accomplish the same ultimate result.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:

1. In a binder construction, a frame, a bull wheel therein, a secondary drive shaft mounted along the side of the frame, said secondary device shaft having a sprocket thereon, elevating and floating conveyor rollers carried by the upper part of said frame and having their axes parallel with said secondary drive shaft, each roller having a sprocket, and

means for actuating said rollers comprising a chain extending from the sprocket on said secondary drive shaft over the sprocket of one of the lower of said rollers and changeably under the sprocket of the upper floating one.

2. In a binder construction, a frame, a bull wheel therein, a secondary drive shaft mounted along the side of the frame, said secondary drive shaft having a sprocket thereon, elevating and floating conveyor rollers carried by the upper part of said frame and having their axes parallel with said secondary drive shaft, each roller having a sprocket, and means for actuating said rollers comprising a chain extending from the sprocket on said secondary drive shaft to the sprockets of said rollers, said chain extending over the elevating conveyor sprocket and under the floating conveyor sprocket and then over an idler sprocket whereby the floating conveyor sprocket may move along the portion of the chain extending between the elevating conveyor sprocket and the idler sprocket and still be driven thereby in any of its positions therealong.

3. In a binder construction, a frame, a bull wheel therein, a secondary drive shaft mounted along the side of said frame, said secondary drive shaft having a sprocket thereon, a platform conveyor extending from said frame, a chain connection from said secondary drive shaft to said platform conveyor, an elevating conveyor on said frame, a chain connection from the front end of said secondary drive shaft to said elevating conveyor, and means for operatively connecting said secondary drive shaft with said bull wheel.

4. In a binder construction, forward and rearward upright frame members, a cross member extending upwardly from the front frame member, then rearwardly and downwardly and again forwardly and having its rear end secured to the rear frame member, and a floating conveyor mounted in bearings, said bearings being floatingly arranged and one of them being supported on said cross member.

5. In a binder construction, forward and rearward upright frame members, a cross member having its forward end secured to the upper end of said front frame member and extending rearwardly therefrom, then downwardly and again forwardly and having its rear end secured to the rear frame member and a floating conveyor mounted in bearings, said bearings being floatingly arranged and one of them being supported on said cross member.

60 CORNELIUS P. HOUTSMA.
